means for opening same including a longitudinal back member 4, side walls 5, overlapping front flaps 6 and 7 having edges substantially equally spaced from the longitudinal median line of the package, and end flaps 8 and 9.

means for sealing ends of the package to the front and side flaps from within the package, including a longitudinal back member 4, side walls 5, overlapping front flaps 6 and 7 having edges substantially equally spaced from the longitudinal median line of the package, and end flaps 8 and 9.

UNITED STATES PATENT OFFICE

ROBERT C. GLENN AND WILLIAM W. FERGUSON, OF RICH HILL, MISSOURI

CIGARETTE PACKAGE

Application filed June 10, 1929. Serial No. 369,820.

Our invention relates to cigarette packages, and more particularly to means for opening containers such as cigarette packages, the principal objects of the invention being to facilitate the opening of a package of cigarettes, to assure operation of opening means, to seal an opening member in the package, and to effect opening with a minimum amount of rupture and distortion of the package.

In accomplishing these and other objects of the invention, we have provided improved details of structure, the preferred forms of which are illustrated in the accompanying drawings, wherein:

Fig. 1 is a perspective view of a sealed package, as of cigarettes, equipped with our improved opening means, and adapted for being opened in accordance with our invention.

Fig. 2 is a similar view illustrating the first steps in opening the package.

Fig. 3 is a perspective view of an opened package.

Fig. 4 is a perspective view of an inner container in process of manufacture, illustrating the location of the opening member, parts of container walls being broken away to show the relation of its members.

Fig. 5 is a perspective view of the package, illustrating the inner container in completed condition, and an outer jacket in process of installation.

Fig. 6 is a fragmentary perspective view of the package, illustrating a sealing stamp in process of installation to seal the inner container flap and the opening member to the package.

Referring in detail to the drawings:

1 designates an inner jacket or container comprising a sheet of foil 2 provided with a lining 3 of relatively light weight paper, and adapted to be folded to form a wrapper including a back member 4, side walls 5, overlapping front flaps or longitudinal covering edge portions 6 and 7 having edges substantially equally spaced from the longitudinal median line of the package, and end flaps 8 and 9.

The ends of the side walls are folded in-

wardly over a bundle of cigarettes 10, and the flap 8 comprises a composite upper or inner end flap formed by the separable overlapping ends of the front edge portions of the foil and paper.

The flap 9 comprises folded portions of the end of the back, and is therefore integral, and is scored as at 11 on the median line of the back to define a severing line and to provide a weakened or perforated connection whereby the halves of the flap may be easily separated, as later described.

The package further comprises an outer jacket or cover 12, including a portion having overlapping ends 13 and 14 secured together as by glue to form a tube for encircling the container and retaining its separable front flaps in engaged position. The jacket further is preferably open at its upper end adjacent the scored flap 9 of the container, and is elongated to provide end portions such as 15 adapted to be folded inwardly and attached to each other to form a closed end or bottom. The jacket is scored on the median line of its front overlapping attached members to provide a weakened portion having a separation line in alignment with the weakened line of the container flap.

Mounted in the package, with its inner end adjacent the base of the flap 9, is an opening member 16 preferably comprising a thread or cord, extending between the flaps 8 and 9 to a position on the outer face of the jacket, in registry with the score lines of the flap 9 and the jacket. The cord is installed in the process of assembling and forming the package, and preferably has its inner end attached by a tab 18 to the inner face of the back of the container adjacent the joint of the back with the flap 9, for more securely anchoring the inner end of the opener at the upper end of the package.

When the formation of the package is completed, a stamp 19 is applied to the upper end thereof, having opposite ends sealingly attached to the jacket and back and front portions of the container, and intermediate portions sealingly attached to the flaps 8 and 9. The stamp thus seals and closes the scoring in the flap 9, and latches the free outer

end of the cord to the package. A portion of the cord extends beyond the front end of the stamp.

An outer sealing envelope 20 of transparent material may be applied to completely enclose the package, the free outer end of the cord being visible through the envelope.

In using the invention, a small opening may be produced in the envelope, as indicated in Fig. 2, to afford access to the end of the cord.

The cord may then be grasped, and application of relatively slight force will cause it to rupture the end flap 9 along its weakened line, the relatively fragile stamp being coincidentally cut.

Attention is called to the fact that the side edges of the stamp, adhering to the flaps 8 and 9 and to the jacket, form a relatively secure binding connection between the several elements, which must be removed or broken to permit displacement of the container flaps for opening the end of the package.

Operation of the cord, in an improved package, tends to displace the flap 9, and tear the stamp from the flaps and jacket. The longitudinal edges of the stamp will, however, ordinarily be retained in engagement with the flaps and jacket, and the flap 9 and stamp will be divided by the cord.

The user will then grasp opposite sides of the package, and break the same on the median line of the jacket, the scoring of the jacket permitting fracture thereof, and the unattached overlapping edges of the container slidably moving away from each other to permit opening of the package on its median line, as illustrated in Fig. 3.

Attention is called to the preferred mounting of the free end of the cord outside of the jacket, and the provision of perforations in the outer flap 9, whereby the cord is enabled to operate only on the median line of the stamp, and splits the stamp, thus avoiding tearing of the same away from the jacket and end flaps. The two half portions of the package are therefore retained in integral condition, hinged on the median line of the back, and may be separated and brought together in use for securely holding the contents until the same is exhausted.

What we claim and desire to secure by Letters Patent is:

1. In a cigarette package including a container having separable overlapping inner and outer end flaps, and a cover provided with a longitudinal score line on the median line of the package, an opener comprising a thread-like member having one end anchored in the package adjacent the base of the outer end flap and extending between said flaps and over the cover.

2. In a cigarette package including an inner jacket having overlapping inner and outer upper end flaps, and an outer jacket

comprising a tubular cover having an open upper end and provided with a weakened line, an opener comprising a thread-like member having one end anchored in the package adjacent the base of said outer end flap and extending between said flaps and over the outer jacket in registry with said weakened line.

3. In a cigarette package including an inner jacket having overlapping inner and outer upper end flaps, and an outer jacket comprising a tubular cover having an open upper end and provided with a weakened portion, an opener comprising a thread-like member having one end anchored in the package adjacent the base of said outer end flap and extending between said flaps and over the outer jacket in registry with the weakened portion thereof.

4. In a cigarette package including an inner container having an upper flap at one end, a lower flap at said end adapted to underlie the upper flap, and overlapping side flaps, a tubular cover provided with a longitudinal score line overlying the overlapping flaps of the inner container, and a separating member mounted on the inner container and extending between said upper and lower flaps in alignment with said score line.

5. In a cigarette package, an inner jacket comprising an integral back and overlapping front edge portions having ends adapted to be folded over an end of the package to form an upper flap, the back having an end adapted to be folded over the upper flap to form an exterior upper end flap and scored on the median line of the package, an outer jacket comprising an integral sheet having longitudinal edges secured together to form a tube and perforated on the median line of the package, and a thread-like opening member having one end anchored to the back of the inner jacket and extending on the median line of the package between the upper flap and the lower flap.

In testimony whereof we affix our signatures.

ROBERT C. GLENN.
WILLIAM W. FERGUSON.
